Primary Examiner — Daniel J Domino(74) *Attorney, Agent, or Firm* — Berenato & White, LLC(57) **CLAIM**

The ornamental design for a display screen or portion thereof with graphical user interface, as shown.

DESCRIPTION

The FIGURE is a front view of a display screen or portion thereof with graphical user interface, showing my new design.

Broken lines shown in the figure illustrate a display screen or portion thereof, and form no part of the claimed design. Other broken lines shown in the figures illustrate portions of a graphical user interface that form no part of the claimed design.
